United States Patent Office

Des. 203,851

Patented Feb. 22, 1966

203,851

SUGAR CONTAINER

Gerald Gulotta, 420 E. 72nd St., New York, N.Y.

Filed July 28, 1965, Ser. No. 86,339

Term of patent 14 years

(Cl. D44—15)

I claim:

The ornamental design for sugar container, substantially as shown.
